UNITED STATES PATENT OFFICE.

ALEXANDER S. RAMAGE, OF DETROIT, MICHIGAN, ASSIGNOR TO FRANK F. BEALL,
ALEXANDER S. RAMAGE, AND BENJAMIN BRISCOE, TRUSTEES, ALL OF DETROIT,
MICHIGAN.

AGITATOR.

Application filed November 3, 1924, Serial No. 747,640. Renewed September 23, 1925.

The present invention relates to an improved fluid mixer and more particularly to mixers used for mixing liquids.

The general purpose of my invention is 5 the provision of a simple and inexpensive mixer of this character that will thoroughly mix the fluids and bring them into intimate contact in a finely divided state. Other purposes are the provision of a mixer capable 10 of treating large quantities of fluids economically and resisting any corrosive action of the fluids.

My invention resides in a mixer comprising a closed vessel having an inlet in the 15 lower portion for the entrance of the fluids, fluid mixing and agitating means within the vessel, and a fluid outlet in the upper portion of the vessel.

More particularly my invention resides in 20 a mixer of the type referred to in which the mixing and agitating means within the vessel comprises a propeller positioned adjacent the liquid inlet and adapted to violently agitate the liquids and propel them 25 upwardly, vanes projecting from the inner walls of the vessel in the path of the liquids, and a perforated plate positioned in the path of the liquids above the vanes.

This invention is particularly adapted for 30 use in the process of purifying crude oil or distillates by treatment with sulfuric acid in connection with which, for clearness in explanation, it will be described, it being understood that my invention is in no way 35 limited to such a use, and it is obvious that many other applications of the mixer are possible.

In the purification process referred to sulfuric acid is introduced into the crude oil 40 or distillate after which the mixture of the two fluids is agitated or stirred in some form of mixer. The effectiveness of the purifying reagents apparently is largely dependent upon the intimacy of the contact between the 45 two fluids resulting from this mixing operation. After completion of the mixing operation the mixture is drawn off, and the acid sludge containing the impurities separated from the purified distillate. The mixers used heretofore have been unsatisfactory in 50 that this mixing process was incomplete, resulting in a product less pure and the use of a larger and more concentrated amount of the acid reagent than is necessary in a

mixer constructed according to my invention. The means by which the above desired results are attained will be fully understood by a consideration of the following description and accompanying drawing, in which—

Fig. 1 is a central vertical section; and 60
Fig. 2 is a horizontal section on plane 2—2 of Fig. 1.

The container or mixing chamber comprises a cylindrical section 1 the ends of which are closed by heads 2 and 3. The heads are secured to the cylindrical portion by pipe flanges 11 and 12. Centrally arranged within the cylinder is a vertical shaft 4 supported by a step bearing 13 and a stuffing box 14 attached to the lower and upper 70 heads, respectively. The central shaft projects through the upper head and a bracket 15 attached to its upper face. The upper end of the shaft is fitted with a bevel pinion 9 meshing with a corresponding pinion 10 attached to a driving shaft 8. Any convenient source of power may be used to drive the mechanism, a pulley 16 for a belt drive being illustrated. The lower portion of the shaft 4 is fitted with stirring blades 80 forming an agitator or propeller 5. This propeller is preferably constructed with a pitch giving it an upward thrust. An inlet 6 is provided in the lower portion of the cylinder 1 directly opposite this propeller 85 for a purpose that will appear later.

Inwardly extending vanes 19 are disposed on the walls of the cylinder in substantially radial relation to the central shaft, with their upper ends extending inwardly into proximity to the shaft. Any number of these vanes may be used but four placed at right angles to each other have been found to be effective in practice. A perforated plate 17 surrounds the shaft and 95 is supported in a horizontal position preferably by means of the vanes 19 and slightly below the outlet 7. The proportions and the construction material used may be varied within wide limits. In practice a mixing cylinder 2 ft. by 10 in. has been used, the propeller being driven at a speed of 300 R. P. M. The cylinder, vanes, heads and other parts may be lead lined when necessary. Phosphor bronze is preferable for 100 use in making the propeller and the central shaft.

In the operation of the device the oil and

acid in the requisite amounts are introduced through pipe 20 and pipe 21, respectively, preferably under pressure, by way of the pipe 18, so as to force them into the path 5 of the revolving propeller. The resulting swirl of liquid is agitated and broken up by being thrown against the vanes; in the course of which the acid and crude oil or distillate are thoroughly mixed and 10 brought into contact in a finely subdivided condition. The liquids are further mixed by passage through the apertures in the perforated plate, after which the mixture issues from the mixer through the outlet 7 15 ready for further treatment. A simple unit of this kind treats continuously several hundred barrels per day. Due to the more intimate contact effected between the liquids, it has been found possible to use dilute in place of the customary concentrated acid, thereby cheapening the process and also making the acid sludge by-product thinner and more valuable. Previous mixers have been devised in which propellers, 20 vanes, perforated plates, and other like elements were used, but my new arrangement comprising the above described elements in 25 the particular cooperative relationship re-

sults in advantages not attainable by generally similar constructions heretofore used. 30

I claim:

1. In a fluid mixer, the combination of a container having a fluid inlet and an outlet in the bottom and top portion thereof, respectively, a stirring device mounted within the container adjacent the inlet, inwardly projecting vanes supported from the inner wall of the container, and a perforated plate disposed within the container in a substantially horizontal plane intermediate 35 the outlet and the vanes.

2. In a liquid mixer, the combination of a container having a fluid inlet and an outlet in the bottom and top portion thereof, respectively, a centrally located vertical shaft mounted therein, a propeller mounted on the shaft adjacent the inlet, inwardly projecting vanes supported from the inner wall of the container, and a perforated plate disposed within the container in a 40 substantially horizontal plane intermediate 45 the outlet and the vanes.

In testimony whereof, I affix my signature.

ALEXANDER S. RAMAGE.
